UNITED STATES PATENT OFFICE.

GEORGE V. ANDERSON, OF WILMINGTON, DELAWARE, ASSIGNOR OF SEVEN-SIXTEENTHS TO CHARLES W. GOUERT, OF SAME PLACE.

LEATHER-GLAZING MACHINE.

SPECIFICATION forming part of Letters Patent No. 426,225, dated April 22, 1890.

Application filed July 11, 1889. Serial No. 317,152. (No model.)

To all whom it may concern:

Be it known that I, GEORGE V. ANDERSON, a citizen of the United States, residing at Wilmington, in the county of New Castle and State of Delaware, have invented a new and useful Improvement in Leather-Glazing Machines, which improvement is fully set forth in the following specification and accompanying drawings.

10 My invention consists of improvements in leather-glazing machines embodying means for operating the agate or glazing-piece, also means for adjusting said agate; furthermore, of means for operating the bed, and finally 15 means for adjusting said bed.

Figure 1 represents a side elevation of a leather-glazing machine embodying my invention. Fig. 2 represents a side elevation of a portion at a right angle to Fig. 1. Fig. 20 3 represents an end view of the horse and adjacent portions on an enlarged scale.

Similar letters and numerals of reference indicate corresponding parts in the several figures.

25 Referring to the drawings, A designates a goose-neck or arm, which is properly supported and has on its upper end the guides or ways B, extending horizontally, and receiving between them the sliding head C, to which 30 motion is imparted by means of the bar or rod D, which is pivoted to said head, and has pivoted to it a lever E, the latter being mounted on a suitable standard E', and having pivoted to it the arm F of a yoke G, which 35 encircles an eccentric H, which is connected with the driving-shaft J.

K designates a cam, which is secured to said driving-shaft and engages with a sliding rod or bar L, said shaft being mounted on a 40 standard M, and said rod being fitted in guides N on the arm A.

P designates a rising and falling bar, which is located below or adjacent to the guides B, and supported on its ends on the parallel arms 45 Q, which are pivoted to said bar, and also to the upper portion of the arm A. One of the arms Q has a limb R secured to it, forming an elbow-lever, which is connected with the sliding bar L by means of a pivoted link S,

whereby rising and falling motions may be 50 imparted to the bar P.

T designates the agate or glazing-piece, which is secured to a rocking or swinging head U in any suitable manner, said head having its axis on a vertical bolt V, which is 55 connected with the sliding head C, and also connected by a pivoted link with a sliding head X, which is fitted on the bar or rod P. The bolt V passes freely through the sliding head C and carries a coiled spring Y and 60 nuts Z Z', said spring bearing against the nut Z and the under side of the sliding head C, so as to hold the agate or piece T down to its work and allow the same to yield when so required, the nut Z being employed to adjust 65 the tension of the spring and the nut Z' to adjust the position of the agate T, it being seen that the sliding heads C X are parallel to each other and serve to move the agate in opposite directions and raise and lower the 70 same, as will be hereinafter set forth.

Below the agate is the bed 1, on which the leather to be glazed is supported, said bed being of the form of an octagonal block and having journals 2, which are mounted on vertical rods 3, the latter being guided in eyes 4 of cross-bars 5, the latter being sustained on standards or uprights 6. The rods 3 pass freely through the eyes 4 and carry the coiled springs 7 and nuts 8 9, said springs bearing 80 against the nuts 8 and eyes 4, whereby the bed is held up to its work and permitted to yield when so required. The nuts 8 are employed to adjust the springs 7, and the nuts 9 to adjust the position of the bed with relation 85 to the agate.

The standards 6 have mounted on them a rotatable rod 10, which is parallel with the bars 5 and carries cams or arms 11, which bear against the lower bar 5, the latter being vertically movable on the standards 6 and held in its uppermost position by said arms 11. When, however, the rod 10 is properly rotated, a handle 12 being provided for that purpose, the arms 11 release the lower bar 5 95 and permit the same to drop, whereby the bed is lowered and cleared of contact of the agate. One of the journals 2 has secured to

it a ratchet 13, with which engages a pawl 14, having an arm 15 mounted loosely on said journal and operated by a rod 16, the latter being connected with an elbow-lever 17, which 5 is mounted on an arm or bracket 18, secured to the adjacent rod 3, said elbow-lever being adjustably connected with an arm 19, which is pivoted to the lever E. The ratchet 13 is engaged by a check-pawl 20, mounted on the rod 3 and serving to prevent improper return motions of the bed 1.

The operation is as follows: Power is applied to the shaft J, whereby the lever E and bar L receive motions, the effect of which is 15 the movement of the sliding head C to and fro and the elevation and depression of the bar P, the sliding head X following the motions of the sliding head C and those of the rising and falling bar P. Owing to the link 20 W, the head U is turned on its axis so that the agate is brought into contact with the leather upon the bed, and then sweeps over the same, remaining in contact therewith. When the agate has completed its throw, the 25 bar P lowers, whereby the head U turns on its axis, thus raising the agate clear of the leather. The slide-head C then makes its return motion, and the agate is carried with it clear of the leather back to the starting-point. 30 Owing to the connection of the elbow-lever 17 with the lever E, the rod 16, previously lowered by the first motion of said lever, is now raised, whereby the pawl 14 presses 35 against the ratchet 13 and rotates the same, thus rotating the bed 1 and presenting another face of the latter to the top, the leather then being placed on said face. The bar P now rises, and the sliding head C begins its 40 advance motion, the agate being again lowered and presented to the leather and carried over the same, thus continuing the glazing operation, which is repeated until the work is finished.

Owing to the rotation of the bed and the 45 presentation of its faces successively to the top, heating of said faces is prevented.

While the spring Y bears downwardly on the head U, and consequently on the agate, it also serves to lower the bar P, and consequently the sliding bar L.

Having thus described my invention, what I claim as new, and desire to secure by Letters Patent, is—

1. In a leather-glazing machine, a rising 55 and falling bar with a sliding head thereon and a sliding head on the frame or arm of the machine, in combination with an agate-carrying head, which is connected with the two sliding heads, and a bed, substantially as described.

2. In a leather-glazing machine, a swinging head carrying an agate and pivotally connected to horizontal sliding heads, one of which is mounted on the frame or arm of the

machine, and the other one is mounted on a 65 rising and falling bar, the said parts being combined substantially as described.

3. In a leather-glazing machine, a sliding head on the frame or arm of the machine and a sliding head on a rising and falling bar, in 70 combination with a bolt which is connected with said first-named sliding head and has the agate-carrying head pivoted to it, and with a link which is pivoted to the second-named sliding head and said agate-carrying 75 head, mechanism, substantially as described, for operating the sliding heads, and a bed, substantially as described.

4. In a leather-glazing machine, a sliding head, a bolt freely fitted thereto, an agate-carrying head, and a spring bearing against said head, in combination with the adjusting-nuts Z Z', mechanism, substantially as described, for operating the said sliding heads, and a bed, substantially as described. 80

5. In a leather-glazing machine, a rising and falling bar, parallel arms supporting the same, and mechanism for operating either of said arms, in combination with a sliding head mounted on said bar, a sliding head mounted 90 on a stationary arm or frame of the machine, and an agate-carrying head connected to both of said sliding heads, and mechanism, substantially as described, for operating said sliding heads, and a bed, substantially as described. 95

6. In a leather-glazing machine, a many-sided bed, a ratchet connected with a journal thereof, a pawl engaged with said ratchet, an arm carrying said pawl, an elbow-lever 100 mounted on the frame of the machine and operating said arm, a lever connected with said elbow-lever, and mechanism, substantially as described, for operating said lever, said parts combined substantially as described. 105

7. In a leather-glazing machine, a bed and means for rotating the same, in combination with a supporting-frame consisting of the bars 5, with the eyes 4, the rods or bolts 3, the standards 6, and the springs 7, said parts being combined substantially as described. 110

8. In a leather-glazing machine, a rotatable bed with its journal-bearings in vertical rods, cross-bars having eyes in their ends, standards on which said cross-bars are supported, 115 nuts working on threads on the vertical rods and between said cross-bars, coil-springs on the vertical rods between the nuts and the lower cross-bar, and a shaft journaled in said standards below the lower cross-bar and provided with cams adapted to bear against said lower cross-bar, said parts being combined substantially as described. 120
